UNITED STATES PATENT OFFICE.

JAMES McCUALEY, OF NEW YORK, N. Y.

COMBINED GAS HEAT AND LIGHT BURNER.

Application filed October 9, 1922. Serial No. 593,415.

To all whom it may concern:

Be it known that I, JAMES McCUALEY, a citizen of the United States, residing in New York, in the county of Bronx and State 5 of New York, have invented certain new and useful Improvements in Combined Gas Heat and Light Burners, of which the following is a specification.

This invention relates to burners for consuming gas, artificial or natural, for the production of heat and light, the principal object being to provide a burner of the Bunsen type but modified to present a cylinder of intensely hot, blue flame.

15 Another object is to provide, in combination with the heater, a burner for producing light which is capable of being used coincidentally or not as may be desired.

In actual practice it is frequently found 20 that many rooms, halls, etc., are provided with only a single gas jet and no provisions for supplying heat which, during the cold season, is often desired. By removing the ordinary burner and substituting one of the 25 type indicated by the invention, such room may be cheaply, quickly and conveniently heated to a comfortable degree of temperature, and, at the same time illuminated, if light be required, without additional burners, fittings or expense of equipment.

30 These objects are fully attained by the burners hereinafter described and shown in the annexed drawings, forming a necessary part of this disclosure, and in which:—

35 Figure 1 is a partial side elevational and vertical sectional view of a combined gas burner made in accordance with the invention.

Figure 2 is a fragmentary bottom plan 40 view thereof.

Figure 3 is an enlarged sectional view of the gas and air inlet control devices.

Figure 4 is a transverse sectional view 45 taken on line 4—4 of Fig. 3.

Referring to the drawings, the numeral 10 designates a nipple which is easily substituted for an ordinary gas burner on the gas inlet or supply pipe 11, and, as will be understood, beyond the cock or control device by which the supply of gas is governed.

The nipple 10 has a control passage 14 controlled by the conical point of a screw 15, having an extending knurled head 16,

the nipple terminating at its upper end 17 55 in a threaded extension 18.

Engaging the extension is an adapter 20 having an axial passage 21 and an exteriorly threaded top 22 to which is fitted the hollow cylindrical stem 23 formed with the base 24 of a mixing chamber 25 having raised arched walls 26 and terminating in an open tube 27.

The stem 23 has opposed openings 28 for the inlet of air, which, mixed with the gas, supplies the necessary oxygen, the combined gases passing into the mixing chamber 25 having perforations 29 in its bottom wall 24, these openings being adjustable in area by a disc 30 rotatable by its raised knurled edge 31, with reference to the chamber, the disc containing perforations 32, corresponding to and registerable with the perforations 29.

The upper end 22 of the adapter is solid 75 and passing through the closed portion are a plurality of passages 34, three being shown, which conduct the mingled gas and air upward within an open conical nozzle 35 formed with the downwardly curved 80 circular base 36 of the burner. For effecting movement of the nozzle 35, the same is provided with a manipulating pin 33.

This base, which is imperforate, has an open upturned beaded edge 37 receptive of 85 a cylinder 40 made of perforated sheet metal or finely meshed gauze netting, through the minute perforations of which the gas escapes outwardly into the atmosphere and which, when the gas is ignited, presents a 90 cylinder of flame.

It is to be noted that the plurality of passages 34 in place of a single control aperture, prevent the hissing or whistling sound 95 commonly heard.

A beaded ring 41 extends inwardly from the top of the perforate cylinder 40, the same acting as a support for an interior, pendant cylindrical deflector 42, arranged concentrically to present an annular gas space 43 between it and the cylinder 40, terminating in an inverted cone 44 spaced correspondingly from the cone 21, its apex being in register with the center of the nozzle 35.

In order to divert the heat from the burning gases downward, there may be a number of rings or washers 45 fitted tightly to the

exterior of the perforate cylinder 40, these rings being made of asbestos and inclined downward at their outer edges as shown, the lower rings containing a slot or opening 46, to conduct flame from the lower portion of the burner to the portions intermediate the rings, as a convenience in igniting.

The foregoing description of the heater 10 elements illustrates its construction and the operation will be readily understood.

The lighting device comprises a gas tip 50 held in the upturned end 51 of an arm 52 having an enlarged hub 53 bored to rotatably 15 engage the nipple 10 between a shoulder 54 and collar 55, the nipple having a lateral opening 56 leading from its enlarged bore 57 and registering with a passage 58 extending from the hub through the arm 52 20 to the tip 50, so that when the arm is swung in one position gas is conveyed to the tip which is ignited as usual, while if a light is not desired, the arm is rotated on the nipple, the interior of the bored hub cutting off 25 the passage of gas through the opening 56 and is limited by a pin 59 fixed in the nipple and extending outward into a recess appropriately formed in the hub 53.

From the foregoing it will be seen that 30 if a light only be required, the screw 15 is turned to close the passage 14 and the arm 58 turned into the position shown in Figs. 1 and 3, the gas cock opened and the gas passing through the tip 50 ignited.

When the heater is used, the screw 15 is 35 turned to permit the gas to flow into the mixing chamber and thence into the space 43. Upon applying a flame to the lower section of the cylinder, it is transmitted

up through the openings 46, forming a 40 cylinder of flame, controllable by adjusting the disc 30 and valve screw as desired.

Obviously the arm may be turned to close the gas passage or not as required.

It will also be evident that if a light jet 45 is not wished for at any time, the nipple 10 may be wholly omitted and the gas pipe 11 screwed directly into the adapter 20, the gas, in this case being controlled by the 50 cock as usual.

Having thus described my invention, explaining the manner of its construction and use, what I claim as new and desire to secure by Letters Patent is:—

1. A heater comprising a perforate cylinder, a deflector spaced concentrically inter-jacent, a mixing chamber on which said cylinder is supported, said chamber having adjustable air inlets, a hollow support for said chamber leading from a gas supply pipe and having a lateral opening through its wall, a hollow arm rotatably mounted on said support, and a gas light tip carried at the end of said arm, the passage in said arm being registrable with the lateral opening in said support. 55

2. The combination with a cylindrical burner adapted to produce heat and having a hollow gas supplying support, of a burner 60 adapted to produce light, a swing arm for said light burner operatively engaged on said support, said arm being hollow and registrable with the lateral opening in the support when in a definite position, and 65 means for limiting the swinging of said arm. 70

In testimony whereof, I have signed my name to this application.

JAMES McCUALEY.
